UNITED STATES PATENT OFFICE.

WAYLAND J. HOWARD, OF ATHOL, MASSACHUSETTS.

ANTISLIPPING DEVICE.

1,178,399.

Specification of Letters Patent.

Patented Apr. 4, 1916.

Application filed July 7, 1915. Serial No. 38,509.

To all whom it may concern:

Be it known that I, WAYLAND J. HOWARD, a citizen of the United States, residing at Athol, in the county of Worcester and State of Massachusetts, have invented new and useful Improvements in Antislipping Devices, of which the following is a specification.

This invention relates to an anti-slipping device of the removal type which may be easily and quickly applied to a shoe when the occasion requires.

The primary object of the invention is to provide an anti-slipping device of this character which is constructed in such a manner as to provide a shoe encircling loop, which may be positioned beneath the sole of the shoe, and upon the vamp thereof, by positioning the toe of the shoe within the loop and moving the shoe in one direction.

Another object of the invention is to provide an anti-slipping device having a flexible element formed of annular link sections adapted to be positioned beneath the sole of a shoe and maintained in frictional engagement therewith by a resilient tubular member connected with the end link sections, and engageable with the vamp of the shoe.

A still further object of the invention is to provide the links comprising the flexible element which is engaged with the sole of the shoe, and which are loosely connected together, with stop shoulders, which engage with the side walls of the links and limit the turning movement of the links when in contact with an uneven surface while the flexible element is under tension.

With these and other objects in view the invention resides in the novel combination and arrangement of parts which will be hereinafter fully described and particularly pointed out in the claims.

The preferred embodiment of the invention has been illustrated in the accompanying drawing, but no restriction is necessarily made to the precise details of construction therein shown, as changes, alterations, and modifications within the scope of the claims may be resorted to when so desired.

In the drawing:—Figure 1 is an end elevation of the front portion of the shoe showing the improved cleat secured thereto. Fig. 2 is a side elevation of the cleat removed from the shoe. Fig. 3 is a detail perspective view of several of the link sec-

tions of the flexible member, which is engageable with the sole of the shoe.

Like characters of reference denote corresponding parts throughout the several views in the drawing.

The numeral 1 designates the front portion of the shoe to which the device is applied which is of the usual well-known type, and 2 the anti-slipping device, which, comprises a resilient tubular member 3 and a flexible member 4 connected thereto. The tubular member 3 in this instance, is a coiled contractile spring which has the end thereof provided with projecting eyes 5.

The flexible member 4 is formed of annular link sections which are loosely connected together and provided upon the peripheral edges thereof with stop shoulders 6 which serve to limit any rotative movement of the links due to frictional contact with an uneven surface when the flexible element is under tension. The end links of the flexible member 4 are connected with the eyes 5 on the tubular member in any suitable manner which would enable the flexible member to communicate movement to the tubular member when the flexible member is rotated beneath the sole of the shoe.

When it is desired to apply the anti-slipping device to a shoe the toe of the shoe is disposed within the loop formed by the flexible member and the tubular member, with the flexible member beneath the toe of the shoe. With the anti-slipping device in this position and the weight of the wearer of the shoe disposed upon the greater number of links in the flexible member, the shoe is moved in a forward direction which causes the stop shoulders on the links to abut against the peripheral edges of the links, while the resilient tubular member 3 exerts a tension upon the flexible element 4 and enables the same to act in the manner to a flexible shaft and cause the tubular member 100 to be rotated over the vamp of the shoe in a direction opposite to that in which the shoe is being moved, thus securing the anti-slipping device to the shoe.

It will, of course, be understood that the anti-slipping device may be removed from the shoe in the reverse manner to that described for applying the same to the shoe, and that when the links of the flexible element are frictionally engaged with the sole of the shoe, and subjected to a tension under the influence of the tubular member, the stop

shoulders upon the links, which allow only a partial rotation of the links when contacting with an uneven surface, and which co-operate with the tubular member 3 in enabling the flexible member to serve as a flexible shaft when it is desired to release the anti-slipping device from the foot of the wearer, provide an efficient means for preventing the wearer of the shoe from slipping upon a slippery surface.

From the foregoing statements it can be clearly seen that an anti-slipping device has been provided which may be quickly applied or easily detached from shoes of various widths.

From the foregoing statements taken in connection with the accompanying drawing, it is at once apparent that an anti-slipping device has been provided which is simple in construction, inexpensive of manufacture and highly efficient in use.

Having thus described the invention what is claimed as new is:—

1. In combination with a shoe, a flexible member adapted to be disposed beneath the toe of the shoe, and a tubular member formed of resilient material and having the ends thereof engaged with the end of the flexible member whereby upon rotation of

the flexible member beneath the toe and sole 30 of the shoe the tubular member may be rolled to position upon the vamp of the shoe.

2. In an anti-slipping device, a flexible member comprising annular links loosely 35 connected for disposition beneath the sole of a shoe, and a contractile spring engaged with the end links of the flexible member and adapted to cause the said flexible member to frictionally engage with the sole of 40 a shoe.

3. In an anti-slipping device, annular links loosely connected to provide a flexible member for disposition beneath the sole of a shoe, a resilient member for disposition 45 upon the vamp of a shoe and having its ends connected with the end links of the flexible member, and shoulders formed on the peripheral edges of said links adapted to limit the movement of said links when contacting 50 with an uneven surface.

In testimony whereof I affix my signature in presence of two witnesses.

WAYLAND J. HOWARD.
